UNITED STATES PATENT OFFICE.

JOSEPH O. CHABOT, OF NORTH ATTLEBORO, MASSACHUSETTS, ASSIGNOR TO GEORGE L. PAINE COMPANY, OF NORTH ATTLEBORO, MASSACHUSETTS.

SEPARABLE BUTTON.

Application filed November 2, 1922. Serial No. 598,569.

To all whom it may concern:

Be it known that I, JOSEPH O. CHABOT, a citizen of the United States, residing at North Attleboro, in the county of Bristol 5 and State of Massachusetts, have invented new and useful Improvements in Separable Buttons, of which the following is a specification.

This invention relates to certain new and 10 useful improvements in separable buttons, and the primary object thereof is to provide a button of this type which embodies improved connecting means for the two members allowing same to be readily connected 15 and disconnected.

A further object of the invention is to provide a simplified form of snap fastening wherein the same is held in position without the use of solder or other extraneous fastening means.

The invention still further aims to provide a separable button which embodies a minimum of parts and which can be cheaply produced and assembled to thereby economize in the cost of manufacture.

The invention also has for its object the provision of a male and female connection which prevents relative turning or rotary movement of the two heads of the button. 30 Still further and other objects will be later set forth and manifested in the course of the following description.

In the drawing:—

Figure 1, is a side elevation of the invention;

Figure 2, is a section on line 2—2 of Figure 1; and

Figure 3, is a section on line 3—3 of Figure 1.

In proceeding in accordance with the present invention, the button is composed of two parts each of which latter has a head 1 and 2 respectively a tubular shank or post 3 and 4, and a disk-like base 5 and 6, the 45 shanks or posts being of substantially rectangular cross section. The heads and bases are of substantially similar contour, although they may vary as to shape or design, as desired.

The base 6 of the female member of the 50 button is formed with a rectangular slot, forming shoulders or fingers 7, while the hollow shank 3 of the male member of the button receives on its interior a flat substantially U-shaped catch member 8. The

catch member 8 has a circular opening 9 in its base to receive a substantially circular inwardly pressed portion 10 formed in one of the sides of the tubular shank 3. This pressed-out portion is of concave-convex 60 cross section and acts to hold the catch 8 in the shank 3 without the use of solder or other extraneous fastening means. The arms 11 of the catch are formed with U-shaped cut-outs 12 so as to receive the shoulders or fingers 7 of the female member. The catch is made of resilient material and has the free ends of its arms 11 curved so as to ride over the fingers 7 and compress the arms 11 to thereby allow the 70 fingers to snap into the cut-outs 12. The catch is also formed of rectangular cross-section and is conformably received in the hollow shank 4, consequently relative turning or rotary movement of the two button 75 members is prevented.

From the foregoing it will be seen that the entire device embodies but three parts namely the two button members and the clasp or catch member, and since the catch 80 member is easily and quickly applied to one of the parts, a very simple and economical structure is produced.

Having thus described my invention, what I claim as new and desire to secure by 85 Letters Patent is:—

1. In a separable button, a pair of members each having a head, a shank of substantially rectangular cross section and a base, the base of one member being formed 90 with a slot providing abutments which extend into the shank interior, and a catch of substantially U-formation having a circular aperture in its base and having its arms formed with U-shaped cut-outs to receive the abutments one of the sides of the shank of the other member being formed with a pressed-out part of concavo-convex cross section which extends into the circular aperture of the catch to secure the latter in 100 position.

2. In a separable button, a pair of members having heads, tubular substantially rectangular shanks and bases, one of the bases being formed with a slot providing shoulders, and a substantially U-shaped catch received in the shank of the other member and having cut-outs to engage the shoulders, the shank of said other member having a pressed-out part engaging between the 105 110

arms of the catch to hold the latter in the shank of the other member.

3. In a separable button, a pair of members having tubular shanks of substantially 5 rectangular cross-section, a catch of substantially rectangular cross-section having one end fitted in one shank and having an opening, a side of said shank having an integral bowed portion of concavo-convex cross sec- 10 tion engaged in the opening of the catch to hold the latter against movement relative to the said shank, the other end of the catch being receivable in the other shank, and means in said last named shank to engage the catch 15 so as to latch the two members together.

4. In a separable button, a pair of members having tubular shanks, a catch having one end received in one shank and having a part formed to lock the catch to the shank, 20 the shank having an integral concavo-convex part formed to engage said locking part to lock the catch to said shank, the opposite end of the catch being receivable in the other shank, and means in said other shank 25 to engage the catch to latch the members together.

5. In a separable button, a pair of members having tubular shanks and a catch in the shank of one member formed to snap

into engagement with the other shank, said 30 catch having an opening and said first named shank having an integral concavo-convex part in one side wall the convex side of which is received in the opening and extends adjacent to the opposite side wall of 35 the first named shank to lock the catch to the shank.

6. In a separable button, a pair of members each having a hollow shank and a base, and a catch having an opening in one end 40 and the latter arranged in one of the shanks, the base of the other shank having a slot of less length than the greatest width of the latter shank to form a pair of abutments which extend into the shank interior and 45 which are for engagement with the free end of the catch, the first named shank having an integral inwardly extending portion engaged in the catch opening to hold the catch in position. 50

In testimony whereof I have signed my name to this specification in the presence of two subscribing witnesses.

JOSEPH O. CHABOT.
